**CONTROL LEVER FOR THE SPEED CHANGE GEAR
OF A BICYCLE OR THE LIKE**

Nobuo Ozaki, Sakai, Osaka, Japan, assignor to Maeda Iron Works Co., Ltd., Osaka Prefecture, Japan, a corporation of Japan

Filed Sept. 30, 1968, Ser. No. 13,776
Claims priority, application Japan May 23, 1968

Term of patent 14 years

Int. Cl. D12—14

U.S. Cl. D90—1

FIG. 1.

FIG. 2.

FIG. 3.

FIG. 5.

FIG. 4.

FIGURE 1 is a front elevation of a control lever for the speed change gear of a bicycle or the like, showing my new design;

FIG. 2 is an end view thereof;

FIG. 3 is a top plan view thereof;

FIG. 4 is a bottom plan view thereof; and

FIG. 5 is a rear elevation thereof.

I claim:

The ornamental design for a control lever for the speed change gear of a bicycle or the like, as shown.
